UNITED STATES PATENT OFFICE.

JOSEPH WEBB, OF BEAVER, PENNSYLVANIA.

DESIGN FOR A GLOBE OR SHADE.

SPECIFICATION forming part of Design No. 20,299, dated November 11, 1890.

Application filed October 2, 1890. Serial No. 366,837. Term of patent 3½ years.

To all whom it may concern:

Be it known that I, JOSEPH WEBB, a subject of the Queen of Great Britain, residing at Beaver, in the county of Beaver and State of Pennsylvania, have invented a certain new and useful Design for Articles of Glassware, such as Globes, Shades, &c., and I do hereby declare the following to be a full, clear, and exact description of the invention, reference being had to the accompanying drawing, which forms part of this specification.

This invention has relation to designs for hollow articles of glassware, such as globes, shades, &c.

The design constituting my invention is particularly applicable to vessels or articles of a semi-spherical shape; and it consists of a series of elliptic lanceolate figures with flattened surfaces and arranged so as to apparently overlap each other.

The accompanying illustration is a side view of a shade embodying my design.

The body A of the shade is of semi-spherical form and bears on its outer surface the elliptic lanceolate flattened projections B B, which are so arranged as to apparently overlap one another.

Having described my design, I claim—

The design for the surface ornamentation of hollow articles of glassware, consisting of a series of apparently overlapping elliptic lanceolate projections, substantially as shown and described.

In testimony that I claim the foregoing I have hereunto set my hand this 20th day of September, 1890.

JOSEPH WEBB.
